UNITED STATES PATENT OFFICE.

CHARLES W. SWAN, OF BOLTON, KANSAS.

PUMP-PACKING.

No. 846,874.

Specification of Letters Patent.

Patented March 12, 1907.

Application filed January 19, 1905. Serial No. 241,794.

To all whom it may concern:

Be it known that I, CHARLES W. SWAN, a citizen of the United States, residing at Bolton, in the county of Montgomery, State of Kansas, have invented certain new and useful Improvements in Pump-Packings, of which the following is a description, reference being had to the accompanying drawing, and to the letters and figures of reference marked thereon.

My invention relates to packings for the working valves or pistons of pumps, and is particularly adapted and intended for use in oil-well pumps and other pumps for use in situations where sand is encountered or is likely to be encountered to such an extent as to make it impossible to use ordinary working valves or pistons on account of the cutting action of the sand.

In oil-well pumps, as well as in other deep-well pumps, it often happens that sand is encountered in such quantity and of such character that it rapidly cuts away and destroys the packing between the working valve or piston and pump-barrel, causing leakage and oftentimes causing the working valve or piston to become choked. Various packings have been devised to overcome the action of the sand, such as leather cups placed about the working valve or piston and rope wound about the working valve or piston below the valve-seat. Under some circumstances met with in practical operation of oil-wells neither of these forms of packing is efficient for any considerable length of time.

My invention has for its object to provide a packing for working valves or pistons which shall be simple and inexpensive in construction and shall be effective to prevent leakage between the working valve or piston and the pump-cylinder, and consequently will prevent the cutting action of any sand which may be encountered.

With this object in view my invention consists in the use of packing-rings of plastic metal or other plastic material, as herein-after described, so constructed and arranged that the movement of the working valve or piston will serve automatically to take up the wear and to prevent leakage.

Referring to the drawings, Figure 1 is a longitudinal sectional view of a working barrel or pump-cylinder, showing my improved

valve in position. Fig. 2 is a longitudinal sectional view of my improved working valve or piston. Fig. 3 is a perspective view showing two of the packing-rings, and Fig. 4 is a perspective view showing one of the hard-metal packing-rings.

In the drawings, 1 is the pump-cylinder, here shown as what is commonly known as the "working" barrel of a pump for oil-wells.

2 is the lower or standing valve at the lower end of the working barrel, through which the oil or other liquid enters the working barrel.

3 is the working or pumping valve, and 4 is the pump-rod. The lower or standing valve 2 may be of any desired construction and is here shown as of a construction commonly employed comprising a cage 5, within which is located a ball 6, which is received in a suitable valve-seat. The working valve or piston 3 is adapted to be reciprocated in the working barrel or pump-cylinder 1 by the pump-rod 4 and comprises a cage 7, in which is carried a ball 8, adapted to seat itself upon the valve-seat 9. The piston is provided below the valve-seat with an extension 10, adapted to carry the packing by which leakage between the piston and walls of the barrel is prevented.

As thus far described, the construction is in general that commonly employed in oil-well pumps; but instead of the leather cups or rope packing commonly carried by the extension 10 I make use of the packing which forms the particular feature of the invention of this application. This packing consists of alternately-arranged rings of hard or non-plastic material and soft or plastic material arranged to be capable of movement longitudinally of the piston, or rather to permit the piston in its reciprocation to have a limited movement through the packing-rings, the construction of the rings and of the portion of the piston on which they are carried being such that by the movement of the piston relative to the rings the hard or non-plastic rings are caused to act upon the soft or plastic rings to upset or expand them. In order that this result may be secured, the soft or plastic rings 11 are formed, as shown in Figs. 2 and 3, with flaring or bell mouths 13 and the hard or non-plastic

rings 12 are formed with tapered ends 14, as shown in Figs. 2 and 4, so as to act as wedges against the flaring or bell mouths 13 of the soft or plastic rings, and thus to upset or spread the soft or plastic rings to take up wear and to cause them to form a tight packing between the piston and the walls of the barrel. The rings 11 and 12 are carried on a reduced portion of the extension 10 and are held in place between a shoulder 15 near the valve-seat 9 and a ring 16, secured on the opposite end of the extension. The ring 16 is preferably screw-threaded on the end of the extension 10 and is preferably held in place by a lock-nut 17, which is preferably held in place by a pin 18, passing through it and the end of the extension. The shoulder 15 is preferably conical, as shown in Fig. 2, and the end of the nut 16 next the packing-rings is preferably square.

The series of rings 11 and 12, which are shown in Figs. 1 and 2 as shown in number, may be of any number desired, preferably not less than three, and in any case should not be sufficient in number or length to fill the space between the shoulder 15 and the ring 16, so that a space 19 will be left either between the upper packing-ring and the shoulder 15 or between the lowest packing-ring and the ring 16, according to the direction in which the piston may be moving. In Figs. 1 and 2 the working valve or piston is shown with the packing-rings in the position they assume just after the piston has begun to move upward, which position relative to the piston they retain until the piston has reached the limit of its upward movement. As the piston descends on its downward stroke the extension 10 slides through the packing-rings until the shoulder 15 comes in contact with the uppermost one of them, the shoulder coming in contact with this uppermost ring with considerable force and by reason of its conical shape tending to upset this ring. The impact of the shoulder 15 on the uppermost ring 11 is transmitted through the series of rings 11 and 12, each hard-metal ring 12 acting to spread or upset the rings above and below it. The continued downward movement of the piston carries the packing-rings downward, and as the piston begins to again move upward the end of the ring 16 is brought against the lowermost packing-ring 11, forcing it against the ring 12 immediately above it and causing it to be upset, the impact of the ring 16 on the lowermost ring 11 being transmitted throughout the series of packing-rings and causing each ring 12, as on the downstroke, to upset the rings 11 above and below it. The upsetting or spreading effect thus produced in the rings 11 will of course depend on the character of the material of which the rings are made and on the length of the space 19, as

well as on the angle at which the flaring or bell mouths 13 of the rings 12 are formed and on the speed of movement of the working valve. The angle of inclination of the flaring or bell mouths 13 is preferably about forty-five degrees.

The rings 11 are of such internal and external diameter as to fit loosely upon the reduced portion of the extension 10 and to fit closely within the barrel 1. The rings 12 are preferably of such interior and exterior diameters as not to fit closely either upon the extension 10 or against the interior of the barrel 1, but to be capable of comparatively free movement.

The square upper end of the ring 16 serves to prevent leakage between the inner surfaces of the rings and the extension 10.

The hard or non-plastic rings 12 are preferably formed of steel, but may be of other metal, it being essential only that they be made of metal which is hard relative to the material of the rings 11. The soft or plastic rings 11 may be made of any metal softer than the metal of which the rings 12 are made—such as Babbitt metal, lead, aluminum, or copper, or soft brass, or hard brass, or other alloys, or of slightly plastic non-metallic material—the metal or alloy or non-metallic material to be used depending upon the metal used for the rings 12 and also depending upon the depth at which the working barrel is to be used.

While I have described my invention as applied to oil-well pumps, it will of course be understood that I do not desire to be limited to its application to any particular kind of pumps, as it may obviously be made use of in pumps of any kind in which it is important to secure a tight joint between the working valve or piston and the pump cylinder or barrel.

Having thus described my invention, what I claim, and desire to secure by Letters Patent, is—

1. In a pump, the combination with the working valve or piston, of a series of packing-rings of plastic and non-plastic metal alternately arranged and mounted to slide on the valve or piston and means for limiting the sliding movement of the rings.

2. In a pump, the combination with the working valve or piston, of a series of packing-rings of plastic and non-plastic material alternately arranged and mounted to slide on the valve or piston, the plastic rings having flaring or bell mouths and the non-plastic rings having tapered ends, and means for limiting the sliding movement of the rings.

3. In a pump, the combination with the working valve or piston of an extension secured thereto, provided at one end with a shoulder and with a removable abutment at the other end, a series of packing-rings carried on the extension and adapted to slide

thereon, the combined thickness of the series of rings being less than the distance between the shoulder and the abutment the shoulder and abutment serving to limit the movement 5 of the packing-rings.

4. In a pump, the combination with the working valve or piston, of an extension secured thereto, provided at one end with a shoulder and with a removable abutment at 10 the other end, a series of packing-rings carried on the extension and adapted to slide thereon the combined thickness of the series of rings being less than the distance between the shoulder and the abutment, comprising alternately-arranged rings of plastic and non-plastic material, the shoulder and abutment 15 serving to limit the movement of the packing-rings.

5. In a pump, the combination with the 20 working valve or piston, of an extension secured thereto, provided at one end with a shoulder and with a removable abutment at the other end, a series of packing-rings carried on the extension and adapted to slide 25 thereon, comprising alternately - arranged rings of plastic and non-plastic material, the rings of plastic material having flaring or bell mouths and the rings of non-plastic material having tapered ends, the shoulder and abutment 30 serving to limit the movement of the packing-rings.

6. In a pump, the combination with the working valve or piston provided with an extension having a tapered shoulder at one end 35 and a removable ring having a square end at the other end, of a series of packing-rings between the shoulder and removable ring mounted to slide on the extension, the combined thickness of the series of rings being 40 less than the distance between the shoulder and the abutment, the sliding movement of the rings being limited by the shoulder and removable ring.

7. In a pump the combination with the 45 working valve or piston provided with an extension having a tapered shoulder at one end and a removable ring having a square end at the other end, of a series of packing-rings between the shoulder and removable ring 50 mounted to slide on the extension, the combined thickness of the series of rings being less than the distance between the shoulder and the abutment, comprising alternately-arranged rings of plastic and non-plastic material, the sliding movement of the rings being 55 limited by the shoulder and removable ring.

8. In a pump, the combination with the working valve or piston provided with an extension having a tapered shoulder at one end 60 and a removable ring having a square end at the other end, of a series of packing-rings between the shoulder and removable ring mounted to slide on the extension, comprising

65 ing alternately-arranged rings of plastic and non-plastic material, the end rings of the series being of plastic material, the sliding movement of the rings being limited by the shoulder and removable ring.

9. In a pump, the combination with the 70 working valve or piston provided with an extension having a tapered shoulder at one end and a removable ring having a square end at the other end, of a series of packing-rings between the shoulder and removable ring 75 mounted to slide on the extension, comprising alternately-arranged rings of plastic and non-plastic material, the plastic rings having flaring or bell mouths and the non-plastic rings having tapered ends, the sliding move- 80 ment of the rings being limited by the shoulder and removable ring.

10. In a pump, the combination with the working valve or piston provided with an extension having a tapered shoulder at one end 85 and a removable ring having a square end at the other end, of a series of packing-rings between the shoulder and removable ring mounted to slide on the extension, comprising alternately-arranged rings of plastic and 90 non-plastic material, the plastic rings having flaring or bell mouths and the non-plastic rings having tapered ends, the end rings of the series being of plastic material, the sliding movement of the rings being limited by 95 the shoulder and removable ring.

11. In a pump, the combination with the working valve or piston, of a pair of packing-rings, one of plastic metal and the other of non - plastic metal, carried by the valve or 100 piston movable relative thereto and so arranged that the impact of the valve or piston upon the rings causes the rings to be forced together to effect the expansion of the rings of plastic metal.

12. In a pump, the combination with the working valve or piston, of a pair of packing-rings, one of plastic material, having a flaring or bell mouth, and the other of non-plastic material, having a tapered end in contact 110 with the flaring or bell mouth of the ring of plastic material, carried by the valve or piston and so arranged that the impact of the valve or piston upon the rings causes the rings to be forced together to effect the ex- 115 pansion of the ring of plastic material.

13. In a pump, the combination with the working valve or piston, of a packing-ring of plastic metal carried by the valve or piston and arranged to be movable thereon, and means whereby the impact of the valve or piston upon the ring of plastic metal causes the upsetting or expansion of the ring of plastic metal.

14. In a pump, the combination with the 125 working valve or piston, of a packing-ring of plastic metal having a flaring or bell mouth carried by the valve or piston and arranged

to be movable thereon, and means carried by the valve or piston adapted to fit the flaring or bell mouth of the ring of plastic metal, so arranged that the impact of the valve or piston upon the ring of plastic metal causes the upsetting or expansion of the ring of plastic metal.

In testimony whereof I affix my signature in presence of two witnesses.

CHARLES W. SWAN.
